(57) **CLAIM**

The ornamental design for a microdermabrasion treatment tip, as shown and described.

DESCRIPTION

FIG. 1 shows a perspective view of a back of a design for a microdermabrasion treatment tip.

FIG. 2 shows a perspective view of a side and front of the design.

FIG. 3 shows a back view of the design.

FIG. 4 shows a front view of the design.

FIG. 5 shows a side view of the design.

FIG. 6 shows another side view of the design, rotated 45 degrees relative to the side view in FIG. 5.

FIG. 7 shows another side view of the design, rotated 90 degrees relative to the side view in FIG. 6; and,

FIG. 8 shows a tip inserts into a microdermabrasion treatment tip mount which is illustrated in broken line for environmental purposes and does not form part of the claimed invention.

The broken lines immediately adjacent to the shaded areas represent the boundaries of the claimed design while all other broken lines in the figures illustrate the portions of the design that form no part of the claim. None of the broken lines form any part of the claimed design.
